UNITED STATES PATENT OFFICE.

EDWARD B. MALLORY, OF WILKINSBURG, PENNSYLVANIA, ASSIGNOR TO ECONOMY FUSE & MANUFACTURING CO., OF PITTSBURGH, PENNSYLVANIA, A CORPORATION OF NEW YORK.

REFILLABLE CARTRIDGE-FUSE.

1,092,498.

Specification of Letters Patent.

Patented Apr. 7, 1914.

Application filed October 3, 1911. Serial No. 652,493.

To all whom it may concern:

Be it known that I, EDWARD B. MALLORY, a citizen of the United States, residing at Wilkinsburg, in the county of Allegheny and State of Pennsylvania, have invented a certain new and useful Improvement in Refillable Cartridge-Fuses, of which the following is a specification.

My invention pertains to refillable cartridge fuses of the electrical class and of a type to accommodate currents of high or low capacity, which are capable of being easily recharged when the fuse blows out, and which can be used repeatedly.

The fundamental object of my invention is the provision of a rechargeable cartridge fuse involving first, the elements of good electrical and mechanical contact between the renewable fuse element and securing cap members: second, means for holding the fuse rigidly in position: and third, means for exposing the ends of said fuse while under contact with the cap members in order to determine the exact ratable capacity of the fuse, and in addition to determine the manufacturer's trade-mark or secret design.

In the accompanying drawing forming a part of this specification Figure 1 is a longitudinal sectional view of the assembled fuse: Fig. 2 is a longitudinal sectional view taken at a right angle to that of Fig. 1: Fig. 3 shows end and side views of the exteriorly threaded ends of modified forms of shells: Fig. 4 is the removable fuse element: Fig. 5 shows a face and edge view of one form of washer used at the end of the shell, and Fig. 6 is a face and edge view of a modified form of washer.

Throughout the different views shown in the drawing the numeral 1 designates a shell made of any suitable non-conducting material and having the ends thereof threaded exteriorly. Seated at the open ends of the shell are removable washer members 2, which are designed and perform the function of a contact and securing means for the end sections of the interiorly positioned and removable fuse element 3. It being essential that this fuse element should be retained in fixed relationship with the other members I have shown two means for preventing rotary movement of the said washers, whereby said fuse will be retained in position. The first means involves a lug 4 formed on

ed to enter a notch 5 in said washer 2, while the modified form involves a lug 6 carried by said washer which enters a notch 7 formed in the extreme outer end of said shell. Either of these two described means are adequate for the purpose intended, and are simple modifications of each other. The fuse element 3 is preferably formed according to the configuration shown in Fig. 4, involving a reduced central portion and enlarged ends, which ends are stamped with the rated capacity of the fuse and likewise with the manufacturer's trade-mark or design. This fuse is preferably positioned diagonally through the shell and the enlarged ends are bent over so as to lie in an approximate plane with said washers, after the adjacent neck or body of said fuse has been passed through the slot 5 of the one form of washer, or else through the slot 8 provided in the modified form, Fig. 6. As clearly shown in Figs. 5 and 6, the slots 5 and 8 are disposed on the lines of chords of the washer 2, these chords extending between the ends of the arcs, preferably of about ninety degrees, but in any case considerably less than one hundred and eighty degrees, so that when the end of the link 3 is bent over the washer 2, an extended contact area is attained between the end of the link (preferably enlarged, as shown in Fig. 4) and the cap 9, thereby providing a good electrical connection and an even seat for the cap. The washers being held against rotary movement by reason of the lug and slot formation said fuse, when positioned as heretofore described, will be prevented from rotating. When thus assembled the screw cap members 9 are turned on over the threaded ends of said shell, and upon coming in contact with the enlarged ends of said fuse element, will insure a positive electrical contact at this point. In order to expose the marked ends of said fuse for proper inspection as to rated capacity, and to guard against fraud in competitive manufacture, I provide the aperture 10 through the outer face of each cap member.

During the final process of assembling as the cap members are being turned on over the ends of the shell they will come in direct contact with the bent over ends of the fuse element, and as this turning on process is continued to the maximum limit of movement of said caps, the oxid that has formed

on the said fuse, due to natural atmospheric causes, will be removed by the frictional engagement of the two said elements, thereby brightening said fuse at the essential point 5 of engagement, and set up a good electrical contact.

What I claim as my invention is:

1. A refillable cartridge fuse comprising a shell, washers removably lying against and 10 entirely closing the open ends of the shell, each washer having an opening communicating with the interior of the shell adjacent the inner periphery of the latter, a fuse within and extending from end to end of 15 the shell and also through the openings in the respective washers, the portions of the fuse which lie in the openings in the washers filling the portions of the openings which communicate with the interior of the shell, 20 and each end of the fuse being provided with a terminal disposed transversely of the fuse and lying in contact with the outer face of the adjacent washer, and caps embracing the fuse terminals and the washers and connected with the shell to hold the terminals 25 and the washers in intimate contact.

2. A refillable cartridge fuse comprising

a shell having threaded ends, washers removably lying against and entirely closing the open ends of the shell, each washer 30 having an opening communicating with the interior of the shell adjacent the inner periphery of the latter, a fuse within and extending from end to end of the shell and through the openings in the respective washers, each end of the fuse being provided with an enlarged terminal disposed transversely of the fuse and lying in contact with the outer face of the adjacent washer and of a size substantially equal to that 40 of the washer, the openings in the washers being filled by the portions of the fuse which lie in said opening, and caps embracing the terminals and the washers to hold them in intimate contact and also provided with 45 threads fitting the threaded ends of the shell.

In testimony whereof, I affix my signature in the presence of two witnesses.

EDWARD B. MALLORY.
